United States Patent Office

Des. 184,931
Patented Apr. 21, 1959

184,931

TOY FIGURE

Alfred Hahn, Forest Hills, N.Y.

Application October 23, 1957, Serial No. 48,210

Term of patent 7 years

(Cl. D34—4)

Fig. 1 is a front elevational view of the toy figure embodying my new design;
Fig. 2 is a side elevational view thereof; and
Fig. 3 is a perspective view of the toy figure.
I claim:
The ornamental design for a toy figure, as shown.
